(57) **CLAIM**

The ornamental design for a corner key, as shown and described.

DESCRIPTION

FIG. 1 is a front, right, and top perspective view of a corner key according to our new design.

FIG. 2 is a rear, left, and bottom perspective view thereof.

FIG. 3 is a front elevation view thereof.

FIG. 4 is a rear elevation view thereof.

FIG. 5 is a right side elevation view thereof, for which a left side elevation view (not shown) is a mirror image.

FIG. 6 is a top plan view thereof; and,

FIG. 7 is a bottom plan view thereof.

1 Claim, 6 Drawing Sheets
